TRANSFORMER VOLTAGE REGULATING
SYSTEMOrin P. McCarty, Pittsfield, Mass., assignor to
General Electric Company, a corporation of
New York

Application March 20, 1936, Serial No. 69,789

21 Claims. (Cl. 171—119)

My invention relates to transformer voltage regulating systems and more particularly to means for changing the connections between the taps of a transformer winding for adjusting the voltage ratio of the transformer.

This application is a continuation in part of my application Serial Number 16,653, filed April 16, 1935, and assigned to the assignee of the present application.

It is usually desirable that the voltage of an electrical circuit be maintained substantially constant under varying load conditions and this is particularly true if the load includes essentially constant potential electrical devices such as incandescent lamps. It is also usually desirable that any voltage regulation of an electrical circuit be accomplished without interrupting the supply of current to the load.

The general object of the invention is to provide an improved transformer tap-changing system which shall be simple in construction and reliable in operation and which can be used to change transformer tap connections without interrupting the transformer load.

Further objects and advantages will be apparent from the following description taken in connection with the accompanying drawings, in which Fig. 1 is a diagrammatic view of a transformer winding provided with tap-changing mechanism constructed and arranged in accordance with the invention; Fig. 2 shows explanatory curves of voltages and currents in various parts of the tap-changing mechanism while a change of tap connections is being made, and Figs. 3, 4 and 5 show modifications of the arrangement shown in Fig. 1.

The transformer winding shown in Fig. 1 includes a common winding 10, a series winding 11 and a voltage winding 12. This transformer winding is connected between a primary or supply circuit 13 and a load or secondary circuit 14. The circuit 14 is connected across the common winding 10 and one side is also connected to some point of the series winding 11 such as its center. The series winding 11 is provided with taps 15, 16, 17, 18 and 19 connected to corresponding fixed contacts 20 on the transformer side of a ratio changing switch 15'. A movable contact 21 on the circuit side of the switch 15' is connected to one side of the circuit 13, the other side of the circuit 13 being connected to the opposite end of the common winding 10. The movable contact 21 of the switch 15' is operated by a Geneva gear 22 driven by a motor 23 through a lost motion connection 24, the motor being controlled

by a contact-making voltmeter 25 connected to the voltage coil 12 which is of course inductively coupled with the common and series transformer windings 10 and 11. If the voltage of the supply circuit rises above its normal desired value, the voltage of the winding 12 will rise and cause the movable contact 26 of the contact-making voltmeter 25 to move onto the fixed contact 35, thus connecting the motor 23 to the voltage winding 12. The motor 23 will then rotate the driving member 28 of the Geneva gear 22 in the direction indicated by the arrow in Fig. 1. This driving member 28 carries a pivoted arm 29 with a pin 30 arranged to engage slots 31 in the driven member 32 of the Geneva gear. The angular travel of the arm 29 relatively to the driving member 28 is limited by pins 33. Rotation of the driving member 28 tensions a spring 34 until just as the pin 30 reaches one of the slots 31 in the driven member 32 when the spring will act to further rotate the driving member 28 rapidly through approximately a half revolution and the driven member 32 a single step in the same direction. This will rapidly transfer the movable contact 21 of the switch 15' to an adjacent contact 20 in a direction to restore the voltage of the load circuit 14 toward its normal value. If the voltage of the primary circuit 13 drops below its desired normal value, then the movable contact 26 of the contact-making voltmeter 25 will move onto the contact 27 of the contact-making voltmeter, thus connecting the motor 23 to the voltage winding 12 and causing the motor to rotate the driving member 28 of the Geneva gear 22 in a direction opposite to that indicated by the arrow in Fig. 1. This will act in the manner already described to transfer the movable contact 21 of the switch 15' rapidly to an adjacent fixed contact 20 so as to raise the voltage of the load circuit towards its desired normal value.

If the movable contact 21 of the switch 15' is transferred from one fixed contact 20 to another while the load current is flowing in the circuits 13 and 14, there would tend to be serious arcing between the contacts and the contacts would thus soon become seriously burned and damaged. To prevent this serious arcing and damage, a by-pass 36 is connected between the movable contact and the series winding, the connection to the series winding being shown at the center or electrical mid-point of the winding. This by-pass 36 may be any suitable impedance, one satisfactory form of which is a resistor which has a normally high resistance but a high negative volt-

age-resistance characteristic so that its resistance will decrease considerably as the voltage across it is increased and will increase considerably as the voltage across it is decreased. A suitable material for this resistor is disclosed in the United States Patent No. 1,822,742, granted September 8, 1931, upon an application of K. B. McEachron and assigned to the assignee of the present application.

When the movable contact 21 of the switch 15' is connected to the same tap to which the resistor 36 is connected, then it is obvious that the resistor 36 is short-circuited by the switch 15'. Under these conditions the resistance of the resistor 36 will be very high, the current through the resistor will be negligible and substantially all of the load current will flow through the switch 15'. When the movable contact 21 is connected to any other tap than that one to which the resistor 36 is connected, then the voltage between these two taps will be impressed across the resistor but this voltage is small and the current through the resistor will therefore be substantially negligible, substantially all the load current still flowing through the switch 15'. When the movable contact 21 is, however, between two of the fixed contacts 20, then the circuit through the switch 15' is open and the full circuit or transformer voltage will be impressed across the resistor 36. With this relatively very high voltage impressed across it, the resistance of the resistor 36 will instantly decrease to a very low value and afford an easy path through the resistor for the load current, thus quickly extinguishing any arc and preventing damage at the switch contacts.

Assume that the movable contact 21 is connected to the same tap 17 to which the resistor 36 is connected and that the movable contact 40 is to be transferred rapidly to the adjacent fixed contact 20 which is connected to the tap 18 as indicated in Fig. 1. The curves shown in Fig. 2 indicate the relative voltage and current conditions in different parts of the tap-changing mechanism which has been described. The broken line 37 of Fig. 2 indicates the instant at which the movable contact 21 leaves the first fixed contact 20 and the line 38 indicates the instant at which the movable contact 21 reaches the second fixed contact 20 to complete a change in tap connections. The curve C₃₉ indicates the current in the tap connection 39 from the tap 18. The curve C₄₀ indicates the current in the tap connection 40 from the tap 17. The curve C₂₁ indicates the current in the movable contact 21 of the switch 15'. The curve C₁₃ indicates the current in the supply circuit 13. The curve E₃₆ indicates the voltage across the resistor 36. The curve C₃₆ indicates the current in the resistor 36. The curve C₁₃ shows that the current in the supply circuit 13 flows continuously and is not interrupted while a change in tap connections is being made. The curves C₃₉, C₄₀, C₂₁ and C₃₆ show that the current flows in the movable contact 21 and the tap connection 40 until the first instant at which the current reaches a zero value after the movable contact 21 has broken its connection with this tap connection 40. The current is then transferred to the resistor 36 until the movable contact 21 reaches the tap connection 39 at which instant the current is transferred from the resistor to this tap connection 39. The curve E₃₆ shows that the voltage across the resistor 36 is at least small enough to be neg-

ligible except while the current is broken through the switch 15'.

The invention provides a very simple and reliable tap-changing mechanism, the provision of the by-pass resistor 36 permitting a very simple form of switch to be used for changing the tap connections without interrupting the current in the load circuit. It is desirable that the switch-operating mechanism and the distance between the fixed contacts 20 be so arranged and proportioned that the load current normally flowing through the movable contact 21 will always have sufficient time to reach a zero value after the movable contact 21 has left one fixed contact 20 and before it reaches an adjacent contact 20. This will assume a transfer of the load current to the resistor 36 and a complete extinguishment of any arc between the contacts before the transfer of the movable contact has been completed.

By connecting, the by-pass impedance 36 to the mid-point of the series winding, the maximum continuous voltage across it, is limited to half the voltage of the series winding.

The modification shown in Fig. 3 is particularly well adapted for use as a branch feeder circuit step voltage regulator. In general principle it is similar to Fig. 1 but it differs therefrom in the following particulars.

The primary relay or contact-making voltmeter 25 is provided with holding coils 41 and 42 which are connected so as to be deenergized when the floating contact 26 is not in engagement with the stationary contacts 27 and 35 but which are energized, respectively, when the floating contact 26 engages the fixed contact 27 or the fixed contact 35. These holding coils may be energized in any suitable manner and as shown they are connected in parallel with the motor energizing circuits. The purpose of these holding coils is to insure a firm non-chattering or arcing contact between the fixed contacts and the floating contact 26. Thus, for example, when the floating contact 26 engages the stationary contact 27 the holding coil 41 is energized, thereby magnetically holding the contact 26 in engagement with the contact 27 and preventing a trembling or vibratory engagement between these contacts, which type of engagement produces injurious pitting and burning of the contact-making voltmeter contacts. Similarly, when contact 26 engages fixed contact 35 the holding coil 42 is energized so as to insure a firm and positive engagement between the contacts. Another result of the holding coils is to cause the contacts of meter 25 to open and close at different voltage values. For example, the voltage resulting in the engagement of contacts 26 and 27 is lower than the voltage required for this separation because of the pull of coil 41.

It will also be noted that the series, secondary, or regulating winding 11 is connected in the supply circuit side of the common or primary winding 10, or in other words that the common winding 10 is always connected directly across the load side of the circuit 14. Consequently, as the number of turns of the common winding across the load circuit is constant the voltage induced in the auxiliary winding 12 is always a direct measure of the load circuit voltage. This is also true of the relation between the windings 10 and 12 of Fig. 1.

The next difference between Fig. 3 and Fig. 1 is that in Fig. 3 the circuit is provided with a manually operable selector switch or terminal board 43. By means of this additional switch it

is possible to have what may be described as a "five in one" regulator. Thus the regulator of Fig. 1 only produces two steps of voltage increase or boost and two steps of voltage decrease or buck and the amounts of buck and boost are equal. However, in Fig. 3 by means of the connection changing switch 43 it is possible to provide selectively five different ranges of regulation. Switch 43 is provided with a movable contact 44 which, as shown, is contacting a fixed contact 45. In this position, one side of the load circuit is connected directly to the outer end of the series winding 11. If the voltage of the entire series winding 11 is 10% of the circuit voltage then the illustrated position of the switch 43 may be termed the 10% boost position because operation of the tap changing movable contact 21 over the contacts 20 can produce a range of regulation from zero to a maximum of 10% boost. In the position in which contact 21 is shown in Fig. 3 a 5% boost is being produced and if the contact 21 is moved counter-clockwise from this position it will successively produce a 7½% voltage boost and a 10% voltage boost, while if it is moved in a clockwise direction it will produce successively a 2½% voltage boost and zero boost as it successively engages the two fixed contacts 20.

The 5% boost which is produced with the parts in the position shown in the drawings is due to the fact that the load current flows from the lower conductor of the supply circuit 13 through the movable contact 21, the tap 17 on the series winding 11, the lower half of the series winding which produces a 5% voltage boost, then through the fixed contact, movable contact 44 and out to the load circuit through the lower conductor of the load circuit 14. The return current path, of course, is through the upper conductors of the load and supply circuits 14 and 13.

If now the movable contact 44 of the connection changing switch 43 is moved clockwise to the adjacent fixed contact 46 the range of regulation which can be secured by the tap changing movable contact 21 will be from a maximum of 7½% boost through zero to a maximum of a 2½% voltage buck. With the contact 21 in the position shown there will be a 2½ voltage boost produced, while if the contact 21 is moved clockwise the boost will first be reduced to zero as the first fixed contact 20 is engaged and as the next contact 20 is engaged there will be a 2½% voltage buck produced. This is because when the movable contact 21 is engaging the second removed clockwise contact 20 the load current flows through the section of the series winding 11 between the taps 19 and 18 in a direction in opposition to the voltage of this portion of the winding thereby producing a voltage buck.

If the movable contact 44 of switch 43 is moved to the next adjacent contact 47 the tap changing circuit will be the equivalent of that shown in Fig. 1 and 5% boost and 5% buck will be produced in equal 2½% steps. This is because the load circuit will then be connected directly to the midpoint of the winding 11 as in Fig. 1. If the movable contact 44 is moved to the next contact 48 it will be possible to secure a 2½% voltage boost and a 7½% voltage buck in 2½% steps. Finally if the movable contact 44 is moved into engagement with the stationary contact 49 the connection will be the reverse of that shown in the drawings and it will be possible to secure a 10% voltage buck in four 2½% steps.

Ordinarily, the range selecting switch 43 will be set at the position giving the range of regula-

tion which is desired for any particular location and circuit in which the regulator is used and in order to change the range of regulation it will be necessary to disconnect the regulator from the circuit so that no current is flowing through the switch 43. However, this is not necessarily essential and if a load current by-pass impedance similar to resistor 36 is connected in shunt with the switch 43 this switch may be operated to change the range of regulation while the regulator is carrying load current. For example, the resistor 50 may be taken as such a resistor. However, resistor 50 serves another purpose which is described immediately below and preferably is not designed to carry the load current of the circuit as this would unnecessarily increase the cost of the regulator.

The primary purpose of resistor 50, which is preferably made of the same material as the resistor 36, is to complete a protective by-pass circuit or shunt around the series winding 11. Very often lightning and transient voltages produced during switching cause such high voltages as would possibly injure the insulation of the series winding 11, as these high voltages travel in surges along the circuit. However, if such a high voltage surge reaches the regulator the resistors 36 and 50 in series completely shunt or by-pass the series winding 11 and due to their characteristic of instantaneously reducing their resistance with increases in applied voltage they form a protective non-linear by-pass for preventing excessive voltages across the series winding 11. It will, of course, be seen that resistors 36 and 50 are, in fact, connected in series across the series winding 11 and directly interconnect the supply circuit 13 and the load circuit 14.

The remaining difference between Fig. 3 and Fig. 1 is that a reactor having a winding 51 and a magnetically saturable core 52 is connected in parallel with the load current by-pass impedance 36, thus forming a by-pass impedance network. This combination of nonlinear resistance 36 and saturable reactor produces an improved load current by-pass because as the arcing current between the contact 21 and the stationary contact 20 is passing through zero the reactor takes the current, thereby extinguishing the arc, and saturates, producing a relatively low effective impedance by-pass. The high voltage peaks produced as the reactor current is passing through zero and which consequently are not reduced by saturation cause the nonlinear resistance 36 to decrease and therefore the resistor acts as a voltage limiting device for the reactor. Such a combination, for a given performance, is considerably less expensive and more practical than a non-linear resistor alone because a saturable reactor which is capable of carrying the load current can be produced for less cost than a non-linear resistance of the same current rating.

In Fig. 4 a capacitor 53 is connected in parallel with the load by-pass resistor 36. The action is similar to the action of a saturable reactor in that after the arcing current has passed through zero and starts rising the capacitor forms a low impedance to the rising current thereby consuming the current and allowing the arc to become extinguished. As the capacitor becomes charged, the voltage across it rises to a value which will cause the resistance of the non-linear resistor 36 to decrease. This non-linear resistor then forms a low impedance path for the flow of current until the moving contact 21 reaches the next fixed

contact and it also acts as a voltage limiting device across the capacitor 53.

Fig. 5 shows a modified form of my invention which is particularly suitable for use on circuits which do not require the fine degree of regulation or the range of regulation produced by step regulators shown in Figs. 1 and 3. It is a simple, rugged, low cost device having but two moving parts and may aptly be described as a branch 10 feeder circuit step voltage booster because in a preferred form it merely provides one step of voltage boost.

Like Figs. 1 and 3, it consists primarily of an auto-transformer having a common winding 10 and a series winding 11. An electro-magnetically operated contactor 54 of the two-position type is provided with two sets of contacts 55 and 56, only one of which sets can be closed at one time. When contacts 55 are closed and contacts 56 are open the series winding 11 is completely out of circuit and the load current flows through the contacts 55. When the contacts 56 are closed and the contacts 55 are open the entire series winding 11 is connected in the load circuit through conductors 51, 58 and contacts 56.

During the positional change of the contacts the load current by-pass impedance 36 carries the current and as shown this impedance is connected from an intermediate point in the series winding 11 to the load circuit 14. The operation of tap changing is therefore similar to the corresponding operation of Figs. 1 and 3.

The booster of Fig. 5 is also provided with an over-voltage protective by-pass 50 which in this case is connected in shunt to the winding 11, or more properly, is connected so as directly to interconnect the supply circuit 13 and the load circuit 14.

Aside from the contactor 54 the only other movable part is the armature and movable contact of a relay 59 forming a part of what may be described as a resonant relay control circuit.

This resonant relay control circuit consists of a capacitor 60, an adjustable saturable core reactor 70 and a resistor 71 connected in series through a switch 72 across a part of the series winding 11. As the voltage of the series winding is directly proportional to the load circuit voltage the voltage applied to the resonant relay circuit is a direct measure of the load voltage. This circuit, including the capacitor 60 and the reactor 70, is capable of being tuned or becoming resonant, it being so arranged that it becomes resonant at a value of voltage determined by the adjustment of the reactor 70 and becomes dissonant at a lower voltage determined by the setting of the adjustable resistance 71. Briefly, the reason that the resonant phenomenon is responsive to voltage is because changes in voltage change the current flowing through the resonant circuit thereby changing the magnetic saturation of the core of the reactor which in turn changes the inductive value of the reactor and at a particular inductive value corresponding to the capacitive value of the capacitor 60 resonance will occur.

The relay 59 is connected across the capacitor and is so arranged that it opens its contacts during resonance and closes them at a voltage value which is lower than the voltage causing resonance.

The contacts of the relay 59 are connected across a portion of the series winding 11 in series with the alternating current input terminals of a rectifier 73 which may be of any well known

type and is shown by way of example as a bridge connected copper oxide rectifier. The direct current output terminals of the rectifier 73 are connected to the operating coil of the contactor 54.

In the operation of Fig. 5, if the switch 72 is closed and the voltage of the load circuit is too low to cause resonance then the contacts of relay 59 will be closed thereby energizing the contactor 54 and causing it to close its contacts 10 56 and open its contacts 55. This thereby connects the series winding 11 in the power circuit and produces a definite predetermined voltage boost. If now the voltage of the power circuit should be too high resonance will occur thereby 15 causing the relay 59 to open its contacts whereby the contactor 54 is deenergized and a strong spring 74 will rapidly snap the contacts 55 closed and open the contacts 56 thereby entirely disconnecting the series winding 11 from the circuit. 20

By means of the adjustments of the reactor 70 and the resistor 71 it is possible, if the series winding 11 produces a 10% voltage boost, to adjust the control circuit so that a 10% voltage boost is produced whenever the voltage of the load circuit drops to 110 volts, for example, thereby bringing it up to 121 volts and to return the contactor to the no-boost position when the voltage reaches 123 volts where it will remain in a no-boost position until the voltage again drops 25 to 110 volts.

Because the accuracy and long life of the resonant relay are not affected by the angle of mounting of the regulator or by vibration, it is ideal for mounting on distribution system poles in the same manner that distribution transformers are mounted.

While I have shown and described particular embodiments of my invention, it will be obvious to those skilled in the art that changes and modifications can be made without departing from my invention and I, therefore, aim in the appended claims to cover all such changes and modifications as fall within the true spirit and scope of my invention.

What I claim as new and desire to secure by Letters Patent of the United States, is:

1. In combination, an alternating current circuit, a transformer including a winding having taps, a ratio changing switch having a transformer side connected to said taps and having a circuit side connected directly to said circuit independently of any part of said winding, and a load current bypass connected between the electrical midpoint of said winding and the circuit side of said switch, said bypass being connected and proportioned to carry the full load current of said winding during a positional change of said switch.

2. A transformer including a winding having taps, a switch having fixed contacts connected to said taps and having but one movable member for successively engaging said fixed contacts so as to change the voltage ratio of said transformer, and an impedance connected to bypass said movable member, said impedance having one end thereof connected to an intermediate point on said winding and being proportioned to carry the full load current of said winding during operation of said switch, said point on said winding being different from the points where current normally enters and leaves said winding whereby the current through said impedance passes through a portion of said winding.

3. In combination, an alternating current cir- 75

cuit, a transformer winding one end of which is permanently connected to said circuit, a two position ratio changing switch having a winding side and a circuit side, said switch being arranged so that in one position it completes a circuit connection through said winding and in another position it interrupts said connection and bypasses said winding, and an impedance connected between substantially the electrical midpoint of said winding and the circuit side of said switch, said impedance being proportioned to carry the full load current of said winding during the positional change of said switch.

4. A transformer including a winding having taps, a switch having a movable contact member for successively making connection to said taps so as to change the voltage ratio of said transformer, and a nonlinear resistor connected to bypass said switch and being proportioned to carry the full load current of said winding during operation of the switch.

5. A transformer including a winding having taps, a switch having a movable contact member for successively making connection to said taps so as to change the voltage ratio of said transformer, and a negative resistance current characteristic impedance connected to bypass said switch and being proportioned to carry the full load current of said winding during operation of the switch.

6. A transformer including a winding having taps, a switch connected to said taps for changing the voltage ratio of the transformer, and normally high resistance means connected to bypass said switch, said means having a high negative voltage-resistance characteristic and being proportioned to carry the full load current of said winding during operation of the switch.

7. A transformer including a winding having taps, a switch connected to said taps for changing the voltage ratio of the transformer, and a normally high resistance resistor connected to by-pass said switch, said resistor having a high negative voltage-resistance characteristic and being proportioned to carry the full load current of said winding during operation of the switch.

8. A transformer including a winding having taps, a switch connected to said taps, means for operating said switch rapidly to change tap connections, and normally high resistance means connected to by-pass said switch, said by-pass means having a high negative voltage-resistance characteristic and being proportioned to carry the full load current of said winding during operation of the switch, and said switch and switch operating means being proportioned and arranged to assure a zero value of current through the switch during the period of its operation.

9. A transformer including a winding having taps, a switch having fixed contacts connected to said taps, said switch also including a movable contact, means for moving said movable contact rapidly from one fixed contact to another to change the voltage ratio of the transformer, and a normally high resistance by-pass connected between said movable contact and said winding, said by-pass having a high negative voltage-resistance characteristic and being proportioned to carry the full load current of said winding during operation of the switch.

10. A transformer including a winding having taps, a switch having a movable contact member for successively making connection to said taps so as to change the voltage ratio of said transformer, and an impedance network having

a plurality of impedances with different volt-ampere characteristics connected between said movable contact member and said winding and being proportioned to carry the full load current of said winding during operation of said switch. 5

11. A transformer including a winding having taps, a switch having a movable contact member for successively making connection to said taps so as to change the voltage ratio of said transformer, and an impedance network connected between said movable contact member and said winding and being proportioned to carry the full load current of said winding during operation of said switch, said impedance network comprising a resistance element and a reactance element 15 connected in parallel.

12. A transformer including a winding having taps, a switch having a movable contact member for successively making connection to said taps so as to change the voltage ratio of said transformer, and an impedance network connected between said movable contact member and said winding and being proportioned to carry the full load current of said winding during operation of said switch, said impedance network comprising a 25 nonlinear resistance-voltage characteristic resistance and an inductive winding connected in parallel.

13. A transformer including a winding having taps, a switch having a movable contact member 30 for successively making connection to said taps so as to change the voltage ratio of said transformer, and an impedance network connected between said movable contact member and said winding and being proportioned to carry the full 35 load current of said winding during operation of said switch, said impedance network comprising a negative resistance-voltage characteristic resistance and a saturable core reactor connected in parallel. 40

14. Voltage adjusting means for an electrical circuit comprising a transformer having a secondary winding adapted to carry the circuit load current and a primary winding energized by the circuit voltage, a two position electromagnetically 45 actuated spring returned contactor adapted in its actuated position to connect said secondary winding in series circuit relation with the circuit and in its returned position to interrupt this connection and bypass said secondary winding, a primary relay sensitive to changes in an electrical characteristic of the circuit for controlling actuation of said contactor from one to the other of the two positions above named, and negative impedance-current characteristic impedance adapt- 50 ed to carry the circuit load current during the period of contactor positional change. 55

15. In combination, a transformer including a winding having taps, a switch connected to said taps for changing the voltage ratio of said transformer, a connection changer connected to said taps for changing the range of adjustment of the voltage of said winding, a switch current bypass connected around said switch, and an overvoltage protective device connected around said connection changer. 60

16. In combination, an alternating current circuit, an autotransformer having a series winding provided with taps, a ratio changing switch connected to said taps and having a movable contact 70 connected to said circuit on one side of said winding, a switch current by-pass impedance connected around said switch, a connection changing range adjuster connected to said taps and having a movable contact connected to said circuit on 75

the other side of said winding, and a negative resistance-voltage characteristic resistance connected as an overvoltage protective means around said connection changing range adjuster.

- 5 17. A transformer including a winding having taps, switching means for successively making individual connection to said taps so as to change the voltage ratio of said transformer, said switching means having apparatus which interrupts the 10 circuit therethrough without making a bridging connection between any pair of taps during a tap changing operation, and non-linear impedance means connected to by-pass said switch and being proportioned to carry the full load current of 15 said winding when said switch is open, said non-linear impedance means being continuously conductive at all values of voltage thereacross and having a percentage change in voltage drop which is always less than any percentage change in load current therethrough.

- 17 18. A transformer including a winding having taps, switching means for successively making individual connection to said taps so as to change the voltage ratio of said transformer, said switching means having apparatus which interrupts the circuit therethrough without making a bridging connection between any pair of taps during a tap changing operation, and non-linear impedance means connected to by-pass said switch and being proportioned to carry the full load current of said winding when said switch is open, said non-linear impedance means being continuously conductive at all values of voltage thereacross and having a voltage which is independent of the rate of change of load current therethrough and which is independent of the quantity of electricity which has passed therethrough.

- 19 19. A transformer including a winding having taps, switching means for successively making individual connection to said taps so as to change the voltage ratio of said transformer, said switching means having apparatus which interrupts the circuit therethrough without making a bridging connection between any pair of taps during a tap changing operation, and a non-linear resistor 45 connected to by-pass said switch and being proportioned to carry the full load current of said

winding during operation of said switch, said resistor being continuously conductive at all values of voltage thereacross and having a resistance which varies instantaneously inversely with variations in the instantaneous value of the current 5 therethrough.

20 20. A transformer including a winding having taps, switching means for successively making individual connection to said taps so as to change the voltage ratio of said transformer, said switching means having apparatus which interrupts the circuit therethrough without making a bridging connection between any pair of taps during a tap changing operation, and non-linear impedance means connected to by-pass said switch and being 15 proportioned to carry the full load current of said winding during operation of said switch, said non-linear impedance means being continuously conductive at all values of voltage thereacross and including a pair of separate impedance elements connected in parallel circuit relation, one of said elements having an impedance which varies inversely with the current therethrough, the other of said elements having an impedance which varies in accordance with the rate of 25 change of current therethrough.

21 21. A transformer including a winding having taps, switching means for successively making individual connection to said taps so as to change the voltage ratio of said transformer, said switching means having apparatus which interrupts the circuit therethrough without making a bridging connection between any pair of taps during a tap changing operation, and non-linear impedance means connected to by-pass said switch and being proportioned to carry the full load current of said winding during operation of said switch, said non-linear impedance means being continuously conductive at all values of voltage thereacross and including a pair of separate impedance elements connected in parallel circuit relation, one of said elements being a resistor whose resistance varies instantaneously inversely with the instantaneous value of the current therethrough, the other of said elements being a saturable core reactor.
